UNITED STATES PATENT OFFICE.

ADRIAN L. PECK, OF SIOUX FALLS, SOUTH DAKOTA.

NEEDLE-THREADER.

SPECIFICATION forming part of Letters Patent No. 772,821, dated October 18, 1904.

Application filed November 10, 1903. Serial No. 180,530. (No model.)

To all whom it may concern:

Be it known that I, ADRIAN L. PECK, a citizen of the United States of America, and a resident of Sioux Falls, in the county of Minnehaha and State of South Dakota, have invented certain new and useful Improvements in Needle-Threaders, of which the following is a specification.

My invention relates to improvements in needle-threaders, and has for its object a device by which a needle may be easily and quickly threaded.

A further object is simplicity of construction and effectiveness in use.

In the accompanying drawings, forming part of this specification, Figure 1 is a perspective view of my invention. Fig. 2 is a detail view showing the guard partly in section. Fig. 3 shows a needle after the thread has been passed through its eye by means of the thread-catcher, and Fig. 4 is a plan view of my invention.

In the drawings let A represent a shank; B, a head on one end of said shank; C, a needle-threader on said head; D, a knife on the side of said head for cutting the thread, and E a hook on the other end of said shank for hanging the device on a support when desired.

The needle-threader C consists of a thread-catcher 2, which is a vertical pin mounted on the head B and formed with a hook 3 on its end for engaging the thread. A guard 6, having sides 7 and 8, which stand vertically, with the thread-catcher between, is fastened on the head B. These sides converge horizontally toward each other, as shown, and the hook 3 on said pin points toward the meeting line of said sides. The sides of the guard hold the needle, with its elongated opening or eye, in position to readily receive the thread as the needle is passed off of the thread-catcher. The upper edge 10 of the guard is curved, as shown, to guide the thread into suitable engagement with the thread-catcher. The spool of thread 9 is revolvably supported on the shank A to enable the thread 9' to be easily unwound.

In use the eye 4 of the needle 5 is passed

over the pin into the position shown in Fig. 1. 50 The end of the thread is then looped around the thread-catcher over the guiding edge of the guard, which causes the thread to bear against the thread-catcher below the hook. The thread is then held firmly in place and 55 the needle lifted off the pin. This movement draws the thread through the eye of the needle, as shown in Fig. 3. The operation of threading the needle is completed by pulling the free end of the thread through the eye. 60

The head may be of any suitable shape. As shown, its side has a circular channel 12, across which the knife-blade D is fastened at 13 for cutting the thread.

The above coactive arrangement of parts 65 for revolvably holding the spool, cutting the thread, and threading the needle quickens the operation of threading the needle and saves time and labor.

Having described my invention, what I 70 claim as new, and desire to protect by Letters Patent, is—

1. A device of the class set forth, consisting of a suitable head, a guard on said head having sides which converge toward each other, the 75 upper edge of said guard being curved to form a guide for the thread, and a thread-catcher between the sides of said guard, consisting of a pin having its upper end formed with a hook which is directed toward the meeting part of 80 the sides of said guard and projects above said guiding edge.

2. A device of the class set forth, consisting of a shank for holding the spool formed with a hook on one end and a head on the other, a 85 guard on said head having sides which converge toward each other, the upper edge of said guard being curved to form a guide for the thread, and a pin between and projecting above the sides of said guard; said pin having 90 a hook formed on its upper end which is directed toward the meeting part of the sides of said guard, for the purposes specified.

3. A device of the class set forth, consisting of a guard having sides which converge toward each other, the upper edge of said guard being curved to form a guide for the thread, a thread-catcher between the sides of said guard, con-

sisting of a pin having its upper end formed with a hook which is directed toward the meeting-line of the sides of said guard and projects above said guiding edge, a shank on which a 5 spool is rotatably supported adjacent to said parts, and means for supporting said guard, thread-catcher and shank.

In testimony whereof I have signed my name to this specification in the presence of two subscribing witnesses.

ADRIAN L. PECK.
